BUBBLE BLOWING WAND

Fred Kort, Los Angeles, Calif., assignor to Imperial Toy Corporation, Los Angeles, Calif.

Filed Nov. 1, 1973, Ser. No. 411,751

Term of patent 14 years

Int. Cl. D21—01

U.S. Cl. D34—15 L

FIG. 1.

FIG. 2.

FIG. 1 is a front elevational view of a bubble blowing wand, showing my new design, and

FIG. 2 is a side elevational view thereof shown partially in section on line 2—2.

The rear view opposite that shown in FIG. 1 has the same appearance of that shown in FIG. 1.

I claim:

The ornamental design for a bubble blowing wand, as shown and described.
